UNITED STATES PATENT OFFICE.

TIMOTHY MULLINS, OF STOUGHTON, MASSACHUSETTS, ASSIGNOR TO HIMSELF AND GEORGE A. WALES, OF SAME PLACE.

SHOE-MAKER'S BENCH.

SPECIFICATION forming part of Letters Patent No. 278,254, dated May 22, 1883.

Application filed March 19, 1883. (No model.)

To all whom it may concern:

Be it known that I, TIMOTHY MULLINS, of Stoughton, in the county of Norfolk and State of Massachusetts, have invented certain Improvements in Shoe-Makers' Bench Attachments or Laps, of which the following is a specification.

This invention relates to the bench attachments used by shoe-makers for supporting a boot or shoe with the last therein bottom upward while the workman is putting on the outer sole, trimming the edge thereof, or performing other operations by hand on the bottom of the boot or shoe. This attachment, which is usually termed a "lap," and sometimes a "knee," is composed of two parallel pieces of wood secured together at one end and separated by a space or slot wide enough to receive the leg and narrower portion of the upper of a boot or shoe, but narrower than the sole and the wider portion of the upper immediately above the sole. Heretofore these pieces have been fixed or non-adjustable with relation to each other, so that to adapt an attachment constructed to be used for men's sizes for smaller work the proximate sides of the side pieces have had to be padded to make the opening between said pieces sufficiently narrow.

My invention consists in making one of said side pieces adjustable with relation to the other, and in providing means for positively holding said adjustable piece in any position to which it may be adjusted, thereby enabling the device to be conveniently adapted to different sizes of boots and shoes, as I will now proceed to describe.

Of the accompanying drawings, forming a part of this specification, Figure 1 represents a side elevation of an attachment embodying my improvement. Fig. 2 represents a top view of the same. Fig. 3 represents a section on line xx , Fig. 2.

The same letters of reference indicate the same parts in all the figures.

In the drawings, a represents a shoemaker's bench of ordinary construction supporting one of my improved attachments, which, for con-

venience of description, I will call a "lap." The lap is composed of two side pieces, b b' , each having an offset, b^2 , at one end, which offsets are abutted together and secured by a bolt, c , as shown in Fig. 2. An opening, d , is thus formed between the side pieces to receive the leg and upper of a boot, e , the leg passing entirely through said opening, as shown in Fig. 1. f represents a transverse block secured to the side pieces, b b' , to support the toe of the boot. The side pieces, b b' , are rigidly attached to the bench a , and the latter has an opening coinciding with the opening d .

In carrying out my invention I provide the side piece b , at its inner edge, with a supplemental piece, b^3 , which forms one of the sides of the opening d . To said supplemental piece are rigidly attached bolts g g , passing through the side piece b , and having thumb-nuts h h on their threaded outer ends, bearing against the outer side of the piece b .

i represents a screw-bolt working in a screw-socket in the piece b , and bearing against the inner side of the supplemental piece b^3 .

It will be seen that by loosening the nuts h the piece b^3 can be pushed inwardly to decrease the width of the opening d , and adapt the sides of the opening to smaller sizes of boots or shoes, while by adjusting the bolt i the piece b^3 can be positively held at any position to which it may be adjusted. The same lap is thus enabled to serve for all sizes of boots or shoes, and the inconvenience of padding to adapt a lap to a smaller size is entirely avoided. The block f is removably secured by dowel-pins k k , attached to the block, and entering orifices l in the side pieces, b b' . Several of said orifices are provided to enable the block f to be adjusted lengthwise of the pieces b b' to make the opening d shorter when it is made narrower by the adjustment of the piece b^3 .

I claim—

1. The improved bench attachment or lap having the opening d , the rigid piece b , forming one side, and the movable supplemental piece b^3 , forming the other side, of said opening, and means for adjusting said supplement.

al piece laterally and positively holding it at any position to which it may be adjusted, as set forth.

2. In a shoe-maker's bench, the combination, 5 with the lap having the opening *d*, adjustable piece *b*³, and the rigid piece *b*, of the adjustable block or toe-rest *f*, as set forth.

In testimony whereof I have signed my name

to this specification, in the presence of two subscribing witnesses, this 16th day of March, 1883.

TIMOTHY MULLINS.
